(57) **CLAIM**

The ornamental design for a four wheel electric wheelchair, as shown and described.

DESCRIPTION

2. Four wheel electric wheelchair

2.1 : Front

2.2 : Back

2.3 : Right

2.4 : Left

2.5 : Top

2.6 : Bottom

2.7 : Perspective

2.8 : Another perspective view

The article is a four wheel electric wheelchair which is driven by an electric motor and which one passenger ride by sitting on the seat; the broken lines are for the purpose of illustrating the unclaimed portions of the four wheel electric vehicle, which form no part of the claimed design; the shading indicated by thin lines are intended only to represent the three-dimensional shape of the surfaces of the design.
